UNITED STATES PATENT OFFICE.

JAMES W. ARROWSMITH, OF MORRISTOWN, NEW JERSEY.

INSTEP-SUPPORT.

1,103,464.

Specification of Letters Patent. Patented July 14, 1914.

Application filed May 2, 1910. Serial No. 559,112.

To all whom it may concern:

Be it known that I, JAMES W. ARROWSMITH, a citizen of the United States, and a resident of the city of Morristown, in the county of Morris and State of New Jersey, have invented certain new and useful Improvements in Instep-Supports, of which the following is a specification.

The invention relates to supporters for the arch of the human instep and its objects are, among others, to provide a support of greater elasticity than can be attained by constructing the support of metal of sufficient thickness to support the weight of the wearer, to provide a comparatively soft and flexible support for the middle and side of the instep and to reduce the cost and increase the strength and durability of the device.

20 The invention consists in the construction, combination and arrangement of parts hereinafter described and claimed and illustrated in the accompanying drawings.

In the said drawings Figure 1 is an under 25 side view of a supporter embodying the improvements. Fig. 2 is a vertical medial section on the line 2—2 of Fig. 1.

The main plate A of the supporter is arched from end to end and from side to 30 side in the usual manner, to approximate the under side of the arch of the human instep, but is somewhat flatter than usual, so as to leave room on the top for the elastic supporting cushion B. The inner side of the 35 main plate, instead of extending upwardly in the usual manner is cut off, and terminates in a short upwardly turned portion A', which not only assists in holding the cushion but adds strength to the support at 40 this point.

The elastic cushion B is preferably made of sponge rubber or some other highly resilient substance, so far as the body portion is concerned, and this body portion extends 45 over the plate from side to side, tapering from points forward and back of the front and rear rivets A² respectively to the opposite edge of the plate. The cushion also tapers from the middle toward its edges so 50 as to give a gradual downward curve to the upper surface with its apex at the middle. The side portion B' extends upwardly at an angle of approximately forty-five degrees and has a curved outer edge. This side portion 55 also tapers from the line of junction with the main cushion to the outer edge, and

is preferably reinforced with canvas or some other relatively stiff material E, extending throughout the cushion.

The plate A is provided with a depressed rib C extending longitudinally thereof parallel with its inner edge, and this depressed rib receives a corresponding part of the cushion so as to hold the said cushion against lateral and longitudinal movement. 60 It also tends to strengthen the plate at the middle. The upturned inner edge A' also tends to hold the cushion in position by pressing against the inner edge of the body portion.

By this construction and arrangement a plate of great strength and durability is provided for, and the support given the desired resilience and softness, so that it will not unduly irritate the foot of the wearer. 70 A side portion is also provided which will yield to a much greater degree than could be attained by a metal side portion, and which will adapt itself to the shape of the part of the foot with which it comes in contact 75 and at the same time exert a yielding pressure tending to restore the foot to its normal position.

The support is provided with a suitable flexible non-metallic covering D, and the 80 rivets A² pass through its cover, the cushion near its extremities and the plate and secure all of these parts together.

A specific feature of the invention is the shape of the cushion and its position relative to the plate. It will be observed that the plate extends from the base of the calcaneum or os-calcis to the anterior part of the metatarsus, thus bridging the arch of the instep, and that the cushion is located 90 between the calcaneum and the metatarsus and fills the triangular space occupied by the under surface of the tarsus or middle part of the arch composed of the scaphoid, cuboid and cuneiform bones and the anterior portion of the astragalus. In this manner a yielding cushion is provided for the complex middle portion of the arch which is ordinarily extremely sensitive and painful in cases of flat-foot, and at the same 100 time means for raising the arch are provided in the metallic plate extending across the arch, which, as will be understood, may be bent or worked to raise or lower the arch 105 as desired.

110 What I claim is:

1. The combination of a metallic plate

- adapted to extend from the base of the calcaneum or os-calcis to the anterior part of the metatarsus, said plate approximating the width of the bony structure of the instep arch, and a cushion of non-metallic resilient material superimposed upon said metallic plate, said cushion having a side portion of the same material extending upwardly therefrom and above the highest point of 5 the plate, said plate being provided with a depression near its middle and with a turned up inner edge, said cushion having a portion located in said depression and having a portion of its under surface in contact with the 10 turned up inner edge of the plate.
2. In a device of the character described the combination of a metal plate and a piece of elastic, non-metallic substance superimposed on the said plate and covering its medial portion, the said plate having a groove 15 20

extending longitudinally thereof and the piece of elastic substance having a portion in said groove.

3. In a device of the character described the combination of a metal plate and a piece of elastic, non-metallic substance superimposed on the said plate and covering its medial portion, the said plate having a groove extending longitudinally thereof and the piece of elastic substance having a portion in said groove, and the plate also having an upturned edge extending over a portion of the side of said piece of elastic substance. 25

Witness my hand this 28th day of April 1910, at the city of New York, in the county of New York.

JAMES W. ARROWSMITH.
